BICYCLE WHEEL COVER

Orlando B. Fornataro, 201 Nemo St.,
New Castle, Pa. 16101

Filed June 10, 1970, Ser. No. 23,428

Term of patent 14 years

Int. Cl. D12—14

U.S. Cl. D14—30

Fig. 1

Fig. 2

FIG. 1 is a side view of a bicycle wheel cover showing my new design; and

FIG. 2 is an enlarged edge view looking down on the wheel cover shown in FIG. 1.

The wheel and tire shown in broken lines are included for illustrative purposes only.

I claim:

The ornamental design for a bicycle wheel cover, as shown and described.
